LOCK

Luigi Trevisin, New York, N. Y.

Application July 14, 1932, Serial No. 622,483

2 Claims. (Cl. 70—14)

This invention relates to new and useful improvements in locks and relates more particularly to a combined key and semi-permutation lock.

One of the objects of the invention is to provide a lock which is relatively simple in construction and which will provide means whereby the lock can be opened only by one familiar with the lock, the device being so constructed that ordinary manipulation of the key will not actuate the bolt.

The invention also contemplates the provision of a lock of this kind which may be readily opened by one instructed in its intricacies, the bolt being actuated only when the key is placed in the proper position.

Still another object of the invention is the provision of a lock which cannot be picked or opened without a key, the key also being of an unconventional construction in order that duplicates thereof cannot be readily made.

The invention further contemplates the provision of a lock of the kind above referred to which will provide means for changing the keys at will in order that if a stranger should get possession of the key used and also have knowledge of the combination he nevertheless could not open the lock.

Other objects and advantages of the invention will be hereinafter specifically pointed out, or will become apparent, as the specification proceeds.

With the above indicated objects in view, the invention resides in certain novel constructions, combinations and arrangements of parts, clearly described in the following specification and fully illustrated in the accompanying drawings, which latter show embodiments of the invention as at present preferred.

In said drawings:

Fig. 1 is a perspective view of the embodiment in its preferred form.

Fig. 2 is a horizontal section taken on line 2—2 on Fig. 1.

Fig. 3 is a side elevation of the key for the lock.

Fig. 4 is a perspective view of the outer portion of the casing, the view also showing the position of several of the parts of the device.

Fig. 5 is a perspective view of one of the parts of the device.

Fig. 6 is a perspective view of the inner key housing.

Fig. 7 is a perspective view of the rear side of the bolt structure.

Fig. 8 is a broken transverse vertical section taken through a portion of the lock.

Referring now more particularly to the drawings which illustrate the preferred embodiment of the invention, the device includes a plate or base member 10 having a flanged vertical end portion 11 which is secured flush with the vertical edge of the door to which the lock is secured.

The vertical end portion 11 is provided with a rectangular aperture 12 through which the main portion 13 of the bolt structure 14 passes. This main portion of the bolt structure, which is illustrated in detail in Fig. 7, is provided with a vertical aperture 15 extending from the upper to the lower portion thereof, in which aperture a pair of conventional lock engaging fingers 16 are pivoted in such a fashion that when the bolt is retracted said fingers also retract into the aperture. The bolt structure is further provided with an extension portion 17, said extension portion having an elongated horizontal slot 18 therein. The bolt structure is guided by means of a screw 19 which passes through the slot and which is secured to the base plate 10. Thus the bolt is enabled to travel forwards and backwards the length of the slot 18, all as hereinafter described.

The bolt is adapted to be moved into three positions, one entirely retracted, one partially extended and one fully extended, the latter position being illustrated in Fig. 1. When the bolt is fully retracted it is secured against movement in the following manner: A substantially L shaped locking member 20 which is provided with a horizontal extension portion 21 is pivotally secured to the plate at 22, this member being urged upwards by means of a flat spring 23 which is mounted on the plate at 24. The extension portion 17 of the bolt is provided on its lower side with a notched portion 25 substantially midway between its ends, this notch being engaged by an extension portion 26 on the L shaped locking member 20 when the bolt structure is in a retracted position. This bolt is urged into the retracted position by means of a spring 27 which is mounted on a screw 28, the outer end of the spring engaging a post 29 at the inner terminal of the bolt structure. The opposite end of the spring engages a post 30 mounted on the plate 10, said post also being engaged by the opposite end of the spring 23.

The preferred form of key 31 for the lock is illustrated in detail in Fig. 3 and is provided with a longitudinal aperture 32 extending inwardly from the outer end thereof. The key also is provided with a pair of spaced teeth 33 and 34 respectively. A key guide pin 36 is mounted in a

50

55

pin supporting member 36' secured to the rear side of the plate 10 and extends into the key hole (not illustrated) leading from the outer surface of the door. When the key is inserted in this 5 key hole the pin 36 passes into the aperture 32 of the key and as the key is moved inwards the end thereof engages the surface of a key housing 37 which is illustrated in detail in Fig. 6, and which is secured to the plate 10. This plate is provided 10 with a key aperture 38 and as the key is revolved to the point where the teeth thereof are adjacent to this aperture 38 the key may then be forced into this aperture which is normally closed by means of an apertured disc 40 which is mounted 15 on the pin 36 and is urged outward by means of a spring 41. Thus, a person not familiar with the mechanism of the lock would not be aware of the position to which the key must be rotated before the teeth thereof may pass into the housing. 20 If, however, both teeth of the key pass into the housing the bolt will not be moved. By inserting the key just far enough, however, into the aperture to allow the outer tooth 33 thereof to pass into the housing and the adjacent tooth 34 to remain on the outside thereof, then rotation of the key in a counter-clockwise direction will cause said tooth 34 to first engage the horizontal extension portion 21 of the L shaped locking member 25 thereby forcing it downward and releasing the extension portion 26 of the locking member 30 from the notch portion 25 of the bolt. Further rotation of the key causes the outer tooth 33 to engage the side of a slot 43 on the inner face of the extension portion of the bolt thereby causing the bolt to pass outwards to its partially extended position. To extend the bolt to its maximum extended position the key is revolved again, the inner tooth member 34 again forcing the L shaped locking member downwards, thereby disengaging the extension portion 26 from a second 35 notched portion 44 on the lower side of the bolt. On this second revolution the outer tooth 33 of the key engages a diagonal surface 45 of a cut-a-way portion on the upper edge of the extension 40 portion, thereby moving the bolt structure to its maximum extended position.

On the upper surface of the bolt extension portion at the inner end thereof there is provided a cut-a-way portion 46 and when the bolt has been extended to its maximum outer position the vertical portion 47 of this cut-a-way portion is engaged by a vertical slide member 48 which is urged downwardly by means of a spring 49 mounted on a post 50, the opposite end of the spring engaging a post 51. The slide is carried on a rectangular post 52 which passes through an elongated slot 53 in the slide, the slide being prevented from casual removal by means of a pin 54. Thus, when the bolt is in its maximum position it is secured against retraction by means of this slide.

65 As heretofore stated the bolt is urged to a retracted position by means of the spring 27 and, accordingly, when the slide 48 is retracted, thereby disengaging itself from the vertical portion 47 of the inner end of the bolt, the bolt will be drawn inwards to the midway position where it is stopped by the engagement between the portion 44 of the bolt and the extension portion 26 70 of the L shaped locking member 20. Retraction of the slide member 48 is accomplished in the following manner:

The slide member, which is illustrated in detail in Fig. 5, is provided with an L shaped extension portion 55 having an aperture 56 there-

through. The plate 10 is provided with a housing 57 having a semi-cylindrical key guide 58 and a key aperture 59. A plate 60 is pivotally secured at 61 to the outer surface of the housing 57, said plate having an inwardly extending pin 62 which passes through an elongated slot 63 in the adjacent portion of the housing 57, this pin passing into the aperture 56 in the L shaped portion 55 of the slide 48, all as shown in detail in Fig. 8. Thus, when it is desired to retract the bolt the key is inserted in the semi-cylindrical guide member 58 just far enough so that the outer tooth of the key passes into the housing 57 and the inner tooth 34 remains on the outside. The key is then rotated and the inner tooth 34 engages the pivotally mounted plate 60, thereby raising same upwards. The pin 62, carried by this plate, raises the slide member 48, thereby releasing the bolt and permitting it to retract under the influence of the spring 47 to its central position. The key is then moved into the slot 38 in the housing 37, as at the start, and given a half turn, the inner tooth 34 lowering the locking member 20 and the outer tooth 33 engaging the side of cut-a-way portion 43 of the bolt thereby moving the bolt 25 inwards to the fully retracted position.

I have illustrated the teeth for the key as having scrolls or cut-a-way portions 66, the key aperture 59 in the housing 57 being shaped to receive said key. It is obvious from the previous description that these scrolls or cut-a-way portions in the key and the corresponding scrolls in the key aperture 59 have nothing to do with the actuation of the bolt, these scrolls being designed primarily to prevent the introduction of foreign key into the lock. Accordingly, if it is desired to provide one lock structure and a plurality of keys, only one of which is to be used in one of said locks, a plate having a key aperture therein may be screwed or otherwise secured to the housing 57, and in order to provide a plurality of different locks, a plurality of plates and keys may be prepared. Thus, if it is desired to change the lock so that it cannot be opened by one possessing a former key, a new plate may be inserted on the housing and a different key employed to correspond with this plate.

The hereinbefore described construction admits of considerable modification without departing from the invention; therefore, it is the wish not to be limited to the precise arrangements shown and described, which are as aforesaid, by way of illustration merely. In other words the scope of protection contemplated is to be taken solely from the appended claims, interpreted as broadly as is consistent with the prior art. 55

What I claim is:

1. In a lock of the class described, the combination of a casing, a retractable bolt positioned within said casing, said bolt having a plurality of key engaging portions and stop member engaging slots along the upper and lower edges thereof, and a longitudinal guide slot therein, a guide screw passing through said guide slot, a pivoted stop member mounted below said bolt and adapted to be released upon actuation of a key, a slideable stop member mounted above said bolt and adapted to engage said bolt when the latter is in a fully extended position; said casing having a key slot therein, a key housing mounted within said casing and having a key slot at right angles to the former key slot in order that the key must be given a partial turn after entering the casing, before it may enter the key housing.

2. A lock of the class described including a cas- 75

ing, a longitudinally moveable bolt mounted within said casing, said bolt having key engaging portions and stop member engaging portions along the upper and lower edges thereof, a stop member mounted below said bolt and adapted to be released upon actuation of a key, a slideable stop member mounted above said bolt and adapted to engage said bolt when the latter is in a fully

extended position, said casing having a key slot therein, an internal key housing mounted within said casing and having an offset key slot therein in order that the key must be given a partial turn after entering the casing, before it may enter the key housing.
